UNITED STATES PATENT OFFICE.

VINCENT BENDIX, OF CHICAGO, ILLINOIS.

ENGINE-STARTER.

1,330,834.

Specification of Letters Patent. Patented Feb. 17, 1920.

Application filed December 19, 1917. Serial No. 207,842.

To all whom it may concern:

Be it known that I, VINCENT BENDIX, a citizen of the United States, residing at Chicago, Cook county, Illinois, have invented certain new and useful Improvements in Engine-Starters, of which the following is a specification.

My invention relates to the drive or transmission portion of starting apparatus for 10 the starting of engines, more particularly internal combustion engines, and the general object thereof is to provide simple, efficient and reliable transmission mechanism of this character of novel construction and 15 operation in the respects hereinafter made apparent from the description.

My drive or transmission is of that type exemplified by patents heretofore issued to me such as Patent No. 1,125,935, dated January 26, 1915, which type is characterized by a motor driven member, such as a screw shaft, on which is mounted a driven member such as a pinion adapted to mesh with a part of the engine to be started and capable 25 of longitudinal movement with respect to the screw shaft and of rotary movement therewith. My invention pertains more particularly to the construction and operation of a screw member which is mounted 30 on the screw shaft and of which the pinion proper forms a part. My invention also relates to novel driving means interposed between a motor driven driving shaft and the screw shaft.

35 In the drawings Figure 1 is a sectional elevation of a starting apparatus illustrating a drive or transmission embodying my invention; Figs. 2, 3 and 4 sections on correspondingly numbered section lines of Fig. 1 and Fig. 5 a sectional elevation of a modified form of drive.

It will be understood that my drive or transmission may be operated directly or indirectly by the prime mover, which is herein 45 in the form of an electric motor, and while in the present instance I have shown the same as driven directly by a driving shaft, such as the extended armature shaft of the motor, it will be understood that my invention 50 is not limited to such construction.

Referring to the particular embodiment of my invention as herein shown in Figs. 1 to 4, the driving shaft 1 is the extended armature shaft and is therefore directly 55 driven by the motor. It is journaled at its

outer end in the bearing 2^a of the inclosing casing 2 secured to the motor frame.

Upon the driving shaft is mounted the screw shaft 3 which is here a screw sleeve having the external screw threads 3^a. This screw shaft is operatively connected with the driving shaft 1 by a driving connection, here shown in the form of a friction clutch. This clutch consists of the drum or casing 4 having a hub portion 4^a fitting upon and secured to the driving shaft by means of a key 5. Within this casing is arranged a series of fixed and movable friction plates 6 and 7 respectively, the former being secured to the casing and being held fixedly 70 as respects longitudinal movement by means of the bolts 8. The movable plates 7 are arranged between the plate 6 and have interlocking engagement with and longitudinal movement in grooves 3^b in the inner end of 75 the screw shaft. A yielding pressure is applied to these clutch plates or disks by means of the springs 9 and adjustment of such tension is secured by means of the nuts 10 on the outer ends of these bolts. Thus 80 the power of the motor is transmitted from the driving shaft 1 through said clutch, including the casing 4 and multiple disks 6 and 7. At the outer end of the screw shaft 85 is formed or secured a stop nut or collar 11 against which the screw member abuts and is stopped thereby as hereinafter explained.

The screw member is formed in two main parts, one a screw sleeve 12 internally screw threaded and mounted upon the screw 90 threads of the shaft 3 and adapted to move longitudinally thereof and rotarily therewith and the other the driving member or pinion proper. This screw sleeve is screw threaded for only a portion of the length of 95 its bore, the remaining or smooth portion extending over the smooth or plain portion of the screw shaft beyond the screw threaded portion thereof. At its inner end this sleeve is provided with a weighted disk 13 secured to or formed as a part thereof and adapted to assure the longitudinal movement of the screw member when the screw shaft is rotated.

Upon the screw sleeve is mounted the driving member or pinion 14, the same being splined or keyed to the sleeve by means of the longitudinal key 15 so that the pinion will be rotated positively thereby and therewith (being non-rotarily connected there- 110

with) and also be capable of longitudinal movement with respect thereto. This pinion is held in a normal outward position against the flange 12^a with a yielding pressure as by means of a coiled spring 16 interposed between the inner end of the pinion and a projection at the end of the screw sleeve, which projection is here the weighted disk itself.

10 Describing the operation of my device and beginning the description of a cycle of operation thereof with the parts in their normal or home position shown in Fig. 1, when the electric motor is operated the driving shaft 1 will be rotated and the screw shaft 3 will likewise be rotated through the clutch hereinbefore explained. Thereupon the screw member will be advanced longitudinally to the right and the pinion will mesh 15 with a rotatable member or part of the engine to be started, which is here shown as the teeth 17^a of the fly-wheel 17 of the engine. When the end of the screw sleeve abuts and is stopped by the nut 11 it will 20 partake of the rotary movement of the screw shaft and the fly-wheel will therefore be rotated. When the engine starts on its own power the screw member will be automatically demeshed and returned to normal position.

30 In the event that the teeth of the pinion and of the fly wheel are not in register and the teeth shall thereupon abut end to end, the pinion will be momentarily stopped but 35 the sleeve will continue to move outwardly against the yielding pressure afforded by the spring 16. The result will be a slight rotation of the screw member, whereupon the teeth will be brought into register and the proper 40 meshing obtained. According to this construction the shock or jar occasioned by the abutting of the teeth end to end will be very slight inasmuch as only a small and light portion (that is the light pinion) of the 45 entire screw member will be brought into contact with the fly-wheel or have anything to do with the impact and the slight impact itself will be occasioned or relieved by the spring 16.

50 In Fig. 5 I have shown a modified form of construction in which the corresponding parts are given the same reference characters. This construction is the same as that already described with the exception that 55 a yielding driving connection consisting of a coiled spring is employed in place of the friction clutch illustrated in Fig. 1. According to this construction the driven shaft 1 is operatively connected to the screw shaft 1 is operatively connected to the screw shaft 60 by means of the coiled spring 18 whose ends are anchored to the driving shaft 1 and to the sleeve shaft 3 by the bolts or studs 19 and 20, respectively. In this construction the spring 18 acts as a yielding driving connection and also stores up energy imparted

by the electric motor before the fly-wheel has actually been "broken loose" and the engine thereby started.

I claim:

1. A drive for engine starters comprising a rotatable shaft, and an operating device formed of two parts, one a member mounted on the shaft for rotary movement therewith and longitudinal movement thereof, and the other a driving member mounted 70 on the other member non-rotarily thereof for positive driving therefrom and in unison therewith and for sliding movement longitudinally thereof.

2. A drive for engine starters comprising 80 a rotatable screw shaft, and an operating device formed of two parts, one a sleeve screw-threaded on the shaft for rotary movement therewith and longitudinal movement thereof, and the other a pinion mounted on the 85 sleeve non-rotarily thereof for positive driving therefrom and in unison therewith and for sliding movement longitudinally thereof.

3. A drive for engine starters comprising 90 a motor driven shaft, a rotatable screw shaft rotated thereby and having a rotary movement independent thereof, and an operating device formed of two parts, one a sleeve screw-threaded on the screw shaft for rotary movement therewith and longitudinal movement thereof, and the other a pinion mounted on the sleeve non-rotarily thereof for positive driving therefrom and in 95 unison therewith.

4. A drive for engine starters comprising 100 a motor driven shaft, a rotatable screw shaft rotated thereby and having a rotary movement independent thereof, a yielding driving connection between the two shafts, and an operating device formed of two parts, 105 one a sleeve screw-threaded on the screw shaft for rotary movement therewith and longitudinal movement thereof, and the other a pinion mounted on the sleeve non-rotarily thereof for positive driving therefrom and in unison therewith.

5. A drive for engine starters comprising 110 a motor driven shaft, a hollow screw shaft mounted thereon and capable of rotary movement therewith and rotary movement 115 independent thereof, a screw device mounted on the screw shaft for positive rotary movement therewith and longitudinal movement thereof, said device being formed in two parts, one a control member screw threaded 120 on the screw shaft and the other a driving member mounted to slide longitudinally on the control member and also mounted non-rotarily thereon for positive rotary movement therewith.

6. A drive for engine starters comprising 125 a motor driven shaft, a hollow screw shaft mounted thereon and capable of rotary movement therewith and rotary movement independent thereof, a screw device mounted 130

on the screw shaft for rotary movement therewith and longitudinal movement thereof, said device being formed in two parts, one a control member screw threaded on the 5 screw shaft and the other a driving member mounted to slide longitudinally on the control member and also mounted non-rotarily thereon for positive rotary movement therewith, and yielding means resisting said 10 longitudinal sliding movement of the driving member.

7. A drive for engine starters comprising a motor driven shaft, a hollow screw shaft mounted thereon and capable of rotary 15 movement therewith and rotary movement independent thereof, a screw device mounted on the screw shaft for rotary movement therewith and longitudinal movement thereof, said device being formed in two parts, 20 one a control member screw threaded on the screw shaft and the other a driving member mounted to slide longitudinally on the control member and also mounted non-rotarily thereon for positive rotary movement 25 therewith, and a coiled spring mounted on the control member and bearing against the driving member to resist said longitudinal sliding movement of the latter.

8. A drive for engine starters comprising 30 a motor driven shaft, a hollow screw shaft mounted thereon and capable of rotary movement therewith and rotary movement independent thereof, a screw device mounted on the screw shaft for rotary movement 35 therewith and longitudinal movement thereof, said device being formed in two parts, one a screw threaded sleeve threaded on the screw shaft and the other a pinion mounted on the sleeve non-rotarily thereof for positive 40 driving in unison therewith and for longitudinal sliding movement thereof.

9. A drive for engine starters comprising 45 a motor driven shaft, a hollow screw shaft mounted thereon and capable of rotary movement therewith and rotary movement independent thereof, a screw device mounted on the screw shaft for rotary movement therewith and longitudinal movement thereof, said device being formed in two 50 parts, one a screw threaded sleeve threaded on the screw shaft and the other a pinion mounted non-rotarily on the sleeve by keying thereto for positive driving in unison therewith and for longitudinal sliding movement 55 thereof.

10. A drive for engine starters comprising 60 a motor driven shaft, a hollow screw shaft mounted thereon and capable of rotary movement therewith and rotary movement independent thereof, a screw device mounted on the screw shaft for rotary move-

ment therewith and longitudinal movement thereof, said device being formed in two parts, one a screw threaded sleeve threaded on the screw shaft and the other a pinion 65 mounted non-rotarily on the sleeve by keying thereto for positive driving in unison therewith and for longitudinal sliding movement thereof, and a spring resisting said longitudinal sliding movement. 70

11. A drive for engine starters comprising a motor driven shaft, a hollow screw shaft mounted thereon and capable of rotary movement therewith and rotary movement independent thereof, a screw device 75 mounted on the screw shaft for rotary movement therewith and longitudinal movement thereof, said device being formed in two parts, one a screw threaded sleeve threaded on the screw shaft and the other a pinion 80 mounted non-rotarily on the sleeve by keying thereto for positive driving in unison therewith and for longitudinal sliding movement thereof, said sleeve having at one end a disk, and a spring interposed between the 85 disk and the pinion for resisting the longitudinal movement of the latter.

12. A drive for engine starters comprising a motor driven shaft, a hollow screw shaft mounted thereon and capable of rotary movement therewith and rotary movement independent thereof, a screw device mounted on the screw shaft for rotary movement therewith and longitudinal movement thereof, said device being formed in 90 two parts, one a control member screw threaded on the screw shaft and the other a driving member mounted to slide longitudinally on the control member and also mounted non-rotarily thereon for positive rotary 95 movement therewith, and a yielding driving connection located in the train of mechanism between the motor and the driving member. 100

13. A drive for engine starters comprising 105 a motor driven shaft, a hollow screw shaft mounted thereon and capable of rotary movement therewith and rotary movement independent thereof, a screw device mounted on the screw shaft for rotary movement therewith and longitudinal movement thereof, said device being formed in two parts, one a control member screw threaded on the screw shaft and the other a driving member mounted to slide longitudinally on the 110 control member and also mounted non-rotarily thereon for positive rotary movement therewith, and a yielding driving connection between said motor-driven shaft and the hollow screw shaft. 115

VINCENT BENDIX.
